[57] **CLAIM**

The ornamental design for a window operator, as shown and described.

DESCRIPTION

FIG. 1 is a right side perspective view of a window operator showing our design.

FIG. 2 is a top plan view of the design.

FIG. 3 is a front elevation view of the design.

FIG. 4 is a left side elevation view of the design.

FIG. 5 is a right side elevation view of the design.

FIG. 6 is a right side perspective view of the design according to a second embodiment.

FIG. 7 is a top plan view of the design according to the alternative embodiment.

FIG. 8 is a front elevation view of the design according to the alternative embodiment.

FIG. 9 is a left side elevation view of the design according to the alternative embodiment.

FIG. 10 is a right side elevation view of the design according to the alternative embodiment.

FIG. 11 is a right side perspective view of the design according to a third embodiment.

FIG. 12 is a top plan view of the design according to the alternative embodiment.

FIG. 13 is a front elevation view of the design according to the alternative embodiment.

FIG. 14 is a left side elevation view of the design according to the alternative embodiment.

FIG. 15 is a right side elevation view of the design according to the alternative embodiment.

FIG. 16 is a right side perspective view of the design according to a fourth embodiment.

FIG. 17 is a top plan view of the design according to the alternative embodiment.

FIG. 18 is a front elevation view of the design according to the alternative embodiment.

FIG. 19 is a left side elevation view of the design according to the alternative embodiment; and,

FIG. 20 is a right side elevation view of the design according to the alternative embodiment.

The broken line illustration in the drawing disclosure is for illustrative purposes only and forms no part of the claimed design.
